Atty's

UNITED STATES PATENT OFFICE.

GUSTAV JOHNSON, OF WEST ROXBURY, MASSACHUSETTS, ASSIGNOR, BY MESNE ASSIGNMENTS, TO CARR FASTENER COMPANY, A CORPORATION OF MASSACHUSETTS.

FASTENER.

Application filed January 7, 1927. Serial No. 159,689.

My invention aims to provide improvements in fasteners of the turn button type.

In the drawings, which illustrate a preferred embodiment of the invention:

5 Figure 1 is a front elevation of the complete fastener assembly;

Fig. 2 is a section taken on the line 2—2 of Fig. 1, and being partly in elevation;

10 Fig. 3 is a section taken on the line 3—3 of Fig. 2;

Fig. 4 is a side elevation of the button or head before being attached to the body of the stud; and

15 Fig. 5 is a plan view of the body portion of the stud before the button or head is attached.

Referring to the embodiment of my invention as illustrated in the drawings, I have shown a turn button fastener which comprises a socket A carried by a curtain 1, or other flexible material, and a turn button stud B secured to a rigid support 2, which may be the body of a vehicle or the like.

The socket is substantially the same as shown and more fully described in my co-pending application Serial No. 159,688 filed herewith.

20 The stud includes the pressed metal rigid body portion 3, secured to the support 2 by a screw 4, and a resilient button or head 5 also pressed from sheet metal. Both the head and body portions of the stud are oblong in cross-section, as shown in Fig. 1.

At the outer end of the body portion, I have provided cam surfaces in the form of 25 high spots 6 and low spots 7 (Fig. 5), which cooperate with the button or head 5 in the manner more fully hereinafter described. An aperture 8 surrounded by a curved wall 9 30 (preferably circular) is also provided in the outer end of the body portion 3.

The button or head 5 is provided with integral fingers 10, which pass through the aperture 8 and resiliently engage the wall 9 35 so as to hold the head in position upon the body portion, as shown in Figs. 2 and 3.

These figures are yieldable with the button or head so that, when the button or head is turned, it may move axially to ride up over

the high cam spots 6 and then snap back 50 into the low spots 7. This arrangement reduces the number of parts to a minimum, without sacrificing any of the advantages of a turn button fastener having more parts.

When the grommet or socket A is placed 55 over the body 3 of the stud B, the button or head 5 may be readily turned to the position in the low spots 7, as shown in Figs. 1 and 2, thus effectively locking the stud and socket together. The button or stud is effectively 60 held in the low spots 7 by means of the resiliency and shape of the spring fingers 10, as shown in Fig. 2, and cannot rattle or become shifted from a predetermined position by accident.

65 My invention is not limited to the particular embodiment shown and described.

Claims.

1. A turn button fastener comprising a body portion, an axially shiftable button or 70 head portion, cam means cooperating between the body and head portions to hold the head portion in predetermined positions, said body portion having an aperture adjacent to its outer end and integral laterally 75 yieldable means extending from said button or head portion for resilient engagement with a wall surrounding said aperture to secure said portions together and permit axial movement of one portion relative to the other.

2. A turn button fastener comprising a rigid body portion having an aperture in one end surrounded by a circular wall, a button or head portion having resilient means integral with and extending therefrom into resilient engagement with said circular wall to secure said portions together and cam means cooperating between the top of said body portion and the bottom of said head portion 90 for holding said button against accidental turning movement when turned to a predetermined relation to said body portion.

3. A turn button fastener comprising a rigid body portion having an aperture in one 95 end surrounded by a circular wall, a resilient button or head portion having resilient means integral with and extending there-

from into resilient engagement with said circular wall to secure said portions together, cam means cooperating between the top of said body portion and the bottom of said 5 head portion for holding said button or head portion against accidental turning movement when turned to a predetermined relation to said body portion and said resilient means

having diverging portions which may yield toward each other and permit axial shifting 10 of said button or head portion to permit it to be turned relative to said cam means.

In testimony whereof, I have signed my name to this specification.

GUSTAV JOHNSON.
